UNITED STATES PATENT OFFICE.

JAMES LOCHER, OF DECATUR, ILLINOIS.

AUTOMATIC GRAIN-SCALE.

SPECIFICATION forming part of Letters Patent No. 399,678, dated March 19, 1889.

Application filed May 1, 1888. Serial No. 272,480. (No model.)

To all whom it may concern:

Be it known that I, JAMES LOCHER, a resident of the city of Decatur, county of Macon, and State of Illinois, have invented certain 5 new and useful Improvements in Automatic Grain-Scales, of which the following is a specification.

My invention is adapted to be used in elevators, mills, or wherever it is desired to automatically weigh a continuous flow of grain; and it consists in certain details of construction and combinations of parts, as hereinafter set forth and claimed.

In the drawings accompanying and forming a part of this specification, Figures 1, 2, and 3 are end views of my device, and Fig. 4 is a perspective view of the weight for the scale-beam. Fig. 1 represents the device as it appears after a discharge has been effected and the parts returned to position. Fig. 2 shows how the flow of grain is limited just previous to a discharge, and Fig. 3 shows how a discharge is effected.

The chute *b* below hopper *a* forms permanent pivotal points of suspension for the bivalvular cut-off and flow-regulator *c c*. Legs *d d* on the cut-off co-operate with roller *e* on arm *f* to regulate the flow of grain through the cut-off. The bivalvular weighing-receptacle *i i* is swung in the bifurcate end *g* of the scale-beam, and is connected with the cut-off by means of arms *h h*, which are slotted at *h' h'* to permit a limited degree of independent motion on pins *u u*. The weight 35 comprises two circular disks separately secured on an axial rod, the disks being indicated by *k k* and the rod by *k'*. The disks are internally grooved or recessed to admit the projecting ends of the axle of sheave *l*, 40 which runs on the curved extension *g'* of the scale-beam and supports the weight.

g'' represents the termination of the scale-beam projected at approximate right angles to the general direction of the beam. 45 *s* is an adjustable bolt in the projection *g''*, and *t* are set-nuts for said bolt.

The device is supported by uprights *o o*. One of a pair of pivot-supporting brackets is shown at *p*. (See Fig. 2, where a support is 50 broken away to expose the bracket.)

In Fig. 2 is also seen the preliminary pivot

r and the true pivot *q* of the scale-beam. Incline *m* tends to throw the weight *k* away from the fulcrum as the beam descends. Incline *n* provides a way down which the 55 weight may roll until arrested by stop *n'*.

With the device in the position shown in Fig. 1 the weighing-receptacle fills rapidly until the scale-beam swings on pivot *r* and permits the parts of the cut-off to swing one 60 toward the other. When the fulcrum of the beam is shifted to pivot *q*, the descent of the weighing-receptacle is checked, leaving the roller *e* between the legs of the cut-off, as shown in Fig. 2. The receptacle will now fill 65 slowly until the scale-weight is overbalanced, when the roller will pass from between the legs, the flow will be cut off, and the receptacle will descend and open, as shown in Fig. 3. The force exerted through arms *h h* in opening the receptacle tends to check the downward motion thereof. To neutralize this 70 tendency and insure an instantaneous discharge, the weight is constructed to roll toward the fulcrum at the instant the beam 75 bears on the true pivot, and the beam is slightly to accelerate the motion of the weight.

At the completion of a discharge of the weighing-receptacle the weight rests on incline *m*, and as the empty receptacle is overbalanced the incline starts the weight toward 80 the end of the beam, with the result that all the parts are returned to the position shown in Fig. 1.

The arms *h h* are so constructed that the 85 cut-off will close completely before the receptacle is opened, and remain closed while the receptacle is open. Provision is also made, as shown in Fig. 2, whereby the receptacle is balanced on the true pivot entirely unaffected 90 by its connection with the cut-off.

The opening in the cut-off just previous to a discharge of the receptacle should be small enough to slightly retard the smallest stream likely to pass through the device. This will 95 insure a uniform flow from the cut-off to the receptacle at each bearing of the scale-beam, and so enable accurate account to be made of the falling grain.

Bolt *s*, with its set-nuts *t*, enables the weight 100 to be adjusted on the beam, as will be readily understood.

- Each part of both the cut-off and the weighing-receptacle, in a vain endeavor to attain perfect equilibrium by swinging under its point of suspension, closes automatically and with firmness against its mate, and as the acts of opening and closing are effected by the simultaneous action of two parts moving in opposite directions it is evident that great celerity of motion is easily attained.
- 10 I claim as new and desire to secure by Letters Patent—
1. In automatic grain-scales, in combination, a bivalvular cut-off on a permanent pivot, a bivalvular weighing-receptacle pivoted in a scale-beam below the cut-off, and arms connecting the receptacle with the cut-off, as and for the purpose set forth.
  2. In automatic grain-scales, in combination, a bivalvular cut-off on a permanent pivot, a scale-beam having two pivotal points, a bivalvular weighing-receptacle pivoted in the scale-beam, arms connecting the receptacle with the cut-off, and a stop partaking of the motion of the scale-beam and adapted to temporarily prevent complete closing of the cut-off, as and for the purpose set forth.
  3. In automatic grain-scales, in combination, a bivalvular cut-off on a permanent pivot, a scale-beam having two pivotal points and a shifting weight, a bivalvular weighing-receptacle pivoted in the scale-beam, arms connecting the receptacle with the cut-off, and
- 15 a stop partaking of the motion of the scale-beam and adapted to temporarily prevent complete closing of the cut-off, as and for the purpose set forth.
4. In automatic grain-scales, in combination, cut-off *c c*, scale-beam *g g'*, having pivots *q* and *r*, weighing-receptacle *i i*, pivoted in the scale-beam, arms *h h*, slotted at *h' h'*, weight *k k l* on beam *g g'*, legs *d d* on the cut-off, and roller *e* on arm *f*, as and for the purpose set forth.
5. In automatic grain-scales, in combination with a weighing-receptacle, beam *g*, 45 curved at *g'*, and provided with upward projection *g''*, the weight comprising the opposed disks internally recessed and the interposed sheave, and the adjusting device *s t*, as and for the purpose set forth.
6. In automatic grain-scales, in combination with a weighing-receptacle, beam *g g' g''*, weight *k k l*, and incline *m*, as and for the purpose set forth.
7. In automatic grain-scales, in combination with a weighing-receptacle, beam *g g' g''*, weight *k k l*, inclines *m* and *n*, and stop *n'*, as and for the purpose set forth.

In testimony whereof I sign my name in the presence of two subscribing witnesses.

JAMES LOCHER.
